CLAIM

The ornamental design for a shoe upper, as shown and described.

DESCRIPTION

FIG. 1 is a front perspective view of a shoe upper showing my new design;

FIG. 2 is a second front perspective view thereof;

FIG. 3 is a side view thereof;

FIG. 4 is a rear perspective view thereof; and,

FIG. 5 is a second rear perspective view thereof.

The photographic area is claimed. The broken line immediately surrounding the periphery of the photographic area represents an unclaimed boundary of the design. The broken lines showing the remainder of the shoe are for environmental purposes only and form no part of the claimed design.
